(57) **CLAIM**

The ornamental design for a fish lure, as shown and described.

DESCRIPTION

FIG. 1 is a perspective view of a fish lure showing my new design.

FIG. 2 is a side elevational view thereof, the opposite side being a mirror image.

FIG. 3 is a front end elevational view.

FIG. 4 is a rear end elevational view.

FIG. 5 is a top plan view; and,

FIG. 6 is a bottom view thereof.

The broken line showing of hooks is for illustrative purposes and forms no part of the claimed design.
